UNITED STATES PATENT OFFICE.

JAMES KINNEY, OF CUMBERLAND, WISCONSIN.

SLEIGH.

SPECIFICATION forming part of Letters Patent No. 307,958, dated November 11, 1884.

Application filed July 12, 1884. (No model.)

To all whom it may concern:

Be it known that I, JAMES KINNEY, a citizen of the United States, residing at Cumberland, in the county of Barron and State of Wisconsin, have invented certain new and useful Improvements in Sleighs; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a vertical cross-sectional view of my device. Fig. 2 is a vertical longitudinal sectional view of the same. Fig. 3 is an end view of the part B, and Fig. 4 is a side view of the same. Fig 5 is a plan view of part B, and Fig. 6 is a bottom view of part A.

This invention has relation to that class of road-sleds in which each runner is designed to have some freedom of movement independently in the direction of the draft; and it consists in the construction and novel arrangement of devices, as hereinafter set forth, and pointed out in the appended claims.

In the accompanying drawings, the letter A designates the upper casting, which is designed to be secured to the transverse bar of the sled, and B the lower casting, to which the runner is rigidly fastened. The upper casting, A, consists of the flanged head C and the short leg D, which extends downward from the head. The bottom of the leg C is hollowed out to form a hemispherical socket or cavity, E, in the sides of which, near the margin, are the opposite inwardly-projecting bearings F. These bearings are concave on their inner faces and merge into the margin G at their lower ends. Their upper portions terminate in shallow convex shoulders H. Above these shoulders the full spherical curvature of the socket is preserved. The lower casting, B, consists of the longitudinal plate K and the hemispherical boss L, which is formed on the middle portion of said plate, allowing on each side a flange-bearing, M, adapted to engage the margin G of the socket-leg of the upper casting when the boss is seated in the socket. The margin G or bot-

tom edge of the socket is slightly convex from front to rear, so that a certain amount of rocking action is permitted to the runner. The upper portion, N, of the boss L has its surface 55 fully curved; this portion, however, terminating at each end in a broad and shallow depression, P, and at each side in a shoulder-bearing, S, below which is a lateral recess-way, V, which communicates with the depression 60 P. While each of these depressions communicates with a recess-way on one side, it is cut off from the recess-way on the opposite side by a stop or guard, Z, which is a rise or continuation downward of the upper spherical 65 portion, N, of the boss. When the runner carrying the casting B is to be secured to the leg-casting A, it is turned so that the lateral bearings of the socket will enter by the depressions P the recess-ways of the boss, the 70 upper portion of the boss ascending into the top of the socket. The runner being then turned into correct position, the shoulder-bearings S of the boss will engage the lateral inner bearings, F, of the socket, and the castings 75 will be connected in a secure manner, but such as will allow each runner a certain amount of rocking movement as well as a horizontal turning motion. In this manner a connection is provided which will allow each runner to be 80 moved forward independently of the other in starting a load. In order, however, that the pivotal motion between the runner-casting and the socket shall not be too great, the stops Z are provided. These stops are arranged in 85 reverse relation on the bosses of the opposite runners, so that each runner can advance but a certain distance ahead of the other.

Having described this invention, what I claim, and desire to secure by Letters Patent, 90 is—

1. A sled-leg casting having a socket in its lower end formed with internal lateral bearings and with a convex margin, substantially as specified.
2. The runner attachment for sleds, consisting of the runner-plate B, having the boss formed with end depressions, P, lateral shoulders S, and recess-ways V, and the leg A, having the head C and the socket E, formed with 95 inferior lateral projecting bearings, F, substantially as specified.

3. The runner attachment for sleds, consisting of the detachable interlocking boss, and socket-castings having stops to prevent extra pivotal action, substantially as specified.
- 5 4. A runner attachment for sleds, consisting of a leg-casting having in its bottom a socket formed with a convex margin, and a runner-casting having an interlocking boss adapted to

engage bearings of the socket, substantially as specified.

In testimony whereof I affix my signature in presence of two witnesses.

JAMES KINNEY.
